[57] CLAIM

The ornamental design for a seat with armrests, as shown
and described.

DESCRIPTION

FIG. 1 is an isometric view of a seat with armrests showing
our new design;

FIG. 2 is a right side elevational view thereof, the left side
elevational view being a mirror image of the right side
elevational view;

FIG. 3 is a top plan view thereof;

FIG. 4 is a front elevational view thereof, the rear elevational
view being a mirror image of the front elevational view; and,
FIG. 5 is a bottom plan view thereof.
